RECORDED.

UNITED STATES PATENT OFFICE.

FREDERICK A. WISWELL, OF OAKLAND, CALIFORNIA.

PROCESS FOR RECOVERING PRECIOUS METALS.

1,120,175.

Specification of Letters Patent.

Patented Dec. 8, 1914.

Application filed February 11, 1914. Serial No. 818,064.

To all whom it may concern:

Be it known that I, FREDERICK A. WISWELL, a citizen of the United States, residing at Oakland, in the county of Alameda and State of California, have invented certain new and useful Improvements in Processes for Recovering Precious Metals, of which the following is a specification.

My invention relates to an improved process for extracting and recovering preferably precious metals, such as gold and platinum from sand, gravel or finely divided, or pulverized ores containing them by the use of mercury, in the form of a mercury salt, or metallic mercury, or both, with or without the aid of an externally obtained electric current.

It is well known that gold contained in sand, gravel or pulverized or finely divided ores or rock, as well as gold and platinum in placer deposits, frequently occur in such minute particles as to make their recovery exceedingly difficult, expensive, and often times impossible by the ordinary processes of amalgamation, heretofore employed. The ores of gold and platinum are often of so low a per cent, of metal to the ton of the rock, sand, gravel or the like, that the ordinary smelting processes cannot be carried out profitably. It has also been found that not infrequently the processes of chlorination and cyanidation are too costly for profitable operation of such low grade ores or the like. It is also a well known fact that processes ordinarily employed for carrying out such processes are generally so costly that they cannot be installed where small capital is available.

An important object of this invention is to provide a process of the above mentioned character, which may be advantageously employed to recover precious metals, particularly gold and platinum, from sand, gravel or finely divided or pulverized ores, containing the precious metals in a finely divided state, whereby their recovery will be highly profitable, and the apparatus required to carry out the process will not be too expensive.

A further object of the invention is to provide a process of the above mentioned character, whereby platinum may be extracted from sand, gravel, or pulverized or finely divided ores, containing gold and platinum in a finely divided state, where it

is generally impossible to recover the platinum by the ordinary process of amalgamation, so that both the gold and platinum are recovered, and the two metals readily separated after recovery.

Other objects and advantages of this invention will be apparent during the course of the following description.

In the accompanying drawings forming a part of this specification and in which like numerals are employed to designate like parts throughout the same, and in which I have shown apparatus within which my process may be advantageously carried out, Figure 1 is a central longitudinal sectional view through the apparatus, taken on line 1—1 of Fig. 2, Fig. 2 is a plan view of the same, Fig. 3 is a horizontal sectional view taken on line 3—3 of Fig. 1, Fig. 4 is an elevation of one end of the apparatus, Fig. 5 is a side elevation of the mercury salt treating amalgamator, included in the apparatus, Fig. 6 is a central longitudinal sectional view through the same, Fig. 7 is a side elevation of a rotatable drum included in the same, Fig. 8 is a transverse sectional view taken on line 8—8 of Fig. 7, Fig. 9 is a similar view taken on line 9—9 of Fig. 6, Fig. 10 is a fragmentary central longitudinal section taken through a slightly different form of mercuric salt treating amalgamator, Fig. 11 is a transverse sectional view taken on line 11—11 of Fig. 10, Fig. 12 is a similar view taken on line 12—12 of Fig. 10, and Fig. 13 is a detail view of a contact.

I will first describe the apparatus which may be advantageously employed for carrying out my process.

The numeral 15 designates an upstanding frame, which may be advantageously formed of wood or the like. Suitably mounted in the upper portion of the upstanding frame 15 is a mercury salt treating amalgamator, designated as a whole by the numeral 16. This amalgamator, as more clearly shown in Figs. 5, 6, 7 and 8, includes an outer shell 17, which is preferably cylindrical and horizontally arranged. This outer shell is relatively stationary. The outer shell 17 is preferably formed in two parts 18, provided at their contiguous edges with exterior flanges 19, secured together by bolts 20. Suitable packing may be arranged between these flanges so that the shell will

be air tight. The portions 18 of the shell 17, however, are not insulated from each other, but are electrically connected by the bolts 20, for a reason to be apparent hereinafter. 5 The shell 17 or parts thereof is preferably formed of iron, although other material may be employed.

Rotatably mounted within the shell 17 is a cylindrical drum or cylinder 21, which is 10 preferably formed of iron and rigidly mounted upon a driving shaft 22. The drum 21 is provided with radially extending teeth 23, arranged in spaced annular groups, the teeth in each group being spaced, as 15 clearly illustrated in Figs. 7 and 8. The teeth 23 are preferably tapered and decrease in width outwardly. The shell 17 is provided with internally arranged teeth 24, arranged in spaced annular groups, the teeth 20 in each group being spaced. The teeth 24 are arranged between the teeth 23, as clearly shown in Fig. 6. Formed upon or connected with the opposite ends of the shell 17 are combined stuffing boxes and bearings, including outer tubular casings 25, which receive therethrough the driving shaft 22. These casings 25 are provided with chambers for receiving electrical non-conducting packing 26, through which the shaft 22 30 passes, as shown.

The numeral 27 designates rings, which engage the packing 26, and are moved toward the same by clamping bolts 28.

It is desired that the drum 21 be insulated 35 from the shell 17, and for this purpose insulating material 29 is interposed between the ends of the drum, shaft 22, and the ends of the shell 17, as more clearly shown in Fig. 6. Insulating material 30 is also interposed 40 between the shaft 22 and the rings 27.

As more clearly shown in Fig. 6, the shaft 22 extends axially through the drum 21, and is rigidly connected therewith by means of transverse pins 29', said drum serving to 45 completely cover and protect the shaft against chemical action. The drum 21 may be removed when desired. This drum is provided at its ends with tapered or conical heads 31, which decrease in diameter inwardly, serving as guide means for the material being fed into one end of the shell 17 and discharged from the opposite end thereof. The shell 17 is provided at one end with an enlarged opening, in communication 50 with an inlet pipe 32, carrying a funnel 33 into which a chute 34 discharges, as clearly shown in Fig. 1. At its opposite end an outlet pipe 35 leads into the shell 17, such outlet pipe being provided with a vertical 55 vent pipe 36, serving to prevent the creation of vacuums within the shell 17, whereby the material will freely pass therethrough. The shaft 22 is rotated by a pulley 37, which is driven from a suitable source of power 60 (not shown).

Arranged near and to one side of the funnel 33 is a supply tank 38, for holding and dissolving mercuric chlorid or other chemicals, the same being discharged into the funnel 33 through a spout 39, as clearly 70 illustrated in Fig. 1.

Attention is now called to Figs. 10, 11, and 12, wherein the shell 17 is shown formed in a single part, with its opposite ends open and closed by plates or heads 40, connected therewith by bolts 41, the heads or plates 40 are thoroughly insulated from the shell 17. The shell 17 is provided with inwardly extending teeth 42, preferably of the shape shown in Fig. 12. The drum 21 is of the same construction as hereinabove described, with its teeth 23 operating between the teeth 42. This drum is driven by the shaft 22, which is insulated from the shell 17. Each plate or head 40 is provided with a chamber 80 for receiving electrical non-conducting packing 43, held in place by a ring 44, moved inwardly by clamping bolts 45 or the like. The material supply and discharge means for the drum 21 will remain the same. 90

The numeral 46 designates (see more particularly Figs. 5, 6 and 10) a wire, having connection with one pole of a source of electric current (not shown), such wire being electrically connected with the shell 17 by a binding post 47. A wire 48, electrically connected with the opposite pole of the source of current, is connected with suitably supported contact strip or plate 49, (see Fig. 13), having slidable contact with one end 100 of the shaft 22. It is thus seen that the insulated shell 17 and drum 21 are electrically connected with the opposite poles of the source of current for a purpose to be hereinafter explained. 105

Resting upon the lower portion of the upstanding frame 15 is a stationary upstanding frame 50, upon which is vertically adjustably mounted a supporting frame designated by the numeral 56. The upstanding frame 50 includes four vertical guide standards 51 firmly secured to the frame 50 but slidably fitting into recessed parts or vertical grooves 56' of the adjustable frame 56, as shown in Figs. 2 and 3, thus insuring 110 vertical, central alinement of the frames 50 and 56 with each other while admitting of the latter being raised or lowered, which when suitably adjusted, rests on blocks 55 of desired thickness. Within the frame 56 115 is suitably mounted a horizontal thrust plate 57 and horizontally disposed bearings 58 and 59. Rotatably and centrally mounted within the frame 56 is a vertical tubular shaft 60, receiving material discharged from the pipe 35. The tubular shaft 60 extends axially within a tank or receptacle 61, which is stationary and suitably connected with the upper end of the frame 50, as shown. 120 Rigidly mounted upon the lower portion of 125

the tubular shaft 60 and arranged for rotation within the receptacle 61 are suitably spaced superposed agitator blades 62, which are horizontally arranged with their upper 5 faces beveled or vertically inclined, whereby they will serve to elevate the ore or material, within the receptacle 61, when they are rotated in proper direction. The receptacle 61 is partially filled with metallic mercury, for a purpose to be explained. Rigidly connected with the upper portion of the tubular shaft 60 is a horizontal bevel gear 63, the lower end of the hub of which rests on the horizontal bearing plates 57 10 and supported thereby. It is thus seen that when the horizontal frame 56 is elevated the lower end of the tubular shaft 60 will be moved away from the lower end of the receptacle 61, as will be more fully explained. Rotatably mounted within the bearings 58 and 59 is a horizontal shaft 64, to the inner end of which is rigidly connected a bevel gear 65, engaging the bevel gear 63. 15

25 The numeral 66 designates a pulley which is rigidly mounted upon the shaft 64, while the numeral 67 designates a pulley which is rotatably mounted upon the shaft and arranged near the pulley 66. It is thus seen that a belt may be shifted from the pulley 67 to the pulley 66 and vice versa, for rotating and stopping the shaft 64.

The receptacle 61 is provided near and spaced from its upper end with an outlet 35 pipe 68, which discharges into the vertical tubular shaft 60 of apparatus which is identical with the apparatus including the tubular shaft 60 hereinabove described, for which reason it is thought that no further 40 description of the same is necessary, it being understood that any suitable number of these apparatuses may be connected in tandem or series, as may be found advantageous.

45 In the practice of my process in connection with the apparatus herewith shown and described, the preferably sifted sand, gravel or pulverized ores containing fine particles of the gold, platinum, silver or the like, preferably having water added thereto to form a mass having a pasty consistency, is fed from the chute 34 to the funnel 33, and passes through pipe 32 into the intake end of the shell 17. An aqueous solution of a 50 salt of mercury, preferably mercuric chloride, preferably containing a proper amount of sulfuric acid of the desired strength, is fed from the tank 38 into the funnel 33 and passes therefrom into the shell 17, to engage 55 with the finely divided precious metal containing material. The shaft 22 is preferably rapidly rotated, to effect a corresponding rotation of the drum 21, but the speed of rotation of the shaft 22 is to be determined in view of the character of the material be-

ing treated. I have found that by adding a proper amount of sulfuric acid of suitable strength to the aqueous solution of mercuric chloride such mercuric chloride will not be deteriorated by the sulfuric acid but its chemical action will be aided thereby as will be more fully explained. The aqueous solution of mercuric chloride in the presence of the iron of the shell 17 gives up to the latter its hydrochloric acid, due to the strong affinity 70 that the hydrochloric acid has for iron, said mercuric chloride simultaneously precipitating metallic mercury, which under the peculiar conditions present during the reaction, will actively combine with the gold or platinum. The peculiar activity of the metallic mercury thus obtained, to amalgamate the precious metals, is due partly to the fact that electric energy is generated during the 75 operation. The hydrochloric acid which is formed, as above stated, acts much more readily upon the iron of the shell 17 than upon the fine particles of the precious metals, such action being increased when sulfuric acid is added, which is preferred. 80 As a result of this the iron shell 17 and drum 21 become electro-positive, while the precious metals in the menstruum, become electro-negative. I have found that gold and platinum particles in pulverized ores are 85 ideal substances to fulfil the function of the electro-negative or cathode pole conditions as above stated. The shell 17 and drum 21 are designed and operate to violently agitate the finely divided precious 90 metal carrying material to a degree sufficient to amalgamate the most minute particles of precious metal, when the same are acted upon by the mercuric chloride. It is thus seen that within the shell 17 the process of electrolysis is carried out, the iron shell 17 and drum 21 being electro-positive, while the fine particles of gold, platinum, 95 silver or the like are electro-negative, being the less soluble, whereby the metallic mercury precipitated from the mercuric chloride will deposit on and amalgamate with the precious metals. The deposition of the metallic mercury occurs by voltaic coupling 100 of any of the electro-chemically excited parts of the interior of the iron shell 17 and drum 21 with the precious metals, therefore the toothed drum is rapidly rotated, to compel, as near as possible, every part of the 105 passing pulp of precious metal containing material, including its precious metal particles, to contact with the electro-positive excited parts of the iron shell. As such contact may be, and usually is instantaneous, the quantity of mercury deposited on the 110 particles of precious metal may be comparatively small, particularly when the mercuric chloride solution is weak. The deposition of the metallic mercury upon the particles of precious metal, as a result of the electrolysis 115

of mercuric chlorid, as above indicated, may be substantially aided by the addition of the sulfuric acid, by reason of its greater action upon the iron material of the shell 17 or drum 21, but at the expense of the more rapid destruction of the latter. In some cases, the ores may carry, in addition to the particles of precious metals, combinations of sulfur or the like metals, that it is not desired to save, such for instance as sulfur, arsenic, antimony, etc. The latter are readily soluble in an acid, such as sulfuric acid in suitable quantity, the affinity of which for arsenic and antimony is much greater than for the iron of the agitating parts. In such cases, the sulfid arsenic or antimony, solutions thus obtained, if still carrying free acid, instead of contaminating the metallic mercury, tend to purify the same. The addition of the sulfuric acid, properly diluted, to the aqueous solution of mercuric chlorid, in the tank 38, will result in the simple mixture of the two solutions, without deleterious action on either. Such a mixture is regularly fed to the pulp which is being violently agitated within the shell 17, as above stated, while the pulp is being subjected to the action of the chemical solution, formed of an aqueous solution of mercuric chlorid and sulfuric acid. The chemical solution and ore pulp are preferably subjected to the action of adventitious electric energy or current, the character of which is to be determined in view of the particular character of the material being treated. Either direct or alternating current may be used, but it is preferred to use a direct current having its polarity periodically reversed. As above explained, one pole of the source of current is connected with the drum 21 while the other pole is connected with the shell 17. Inasmuch as iron and platinum are not susceptible to amalgamation with mercury unalloyed with sodium in the absence of a properly applied adventitious electric current, it is obvious that it is advantageous to use such current, to recover the platinum. However, it is not desired that the mercury should combine with the iron of the shell 17 or drum 21.

The shell 17 and drum 21 are insulated from each other, as described, whereby they will alternate in polarity synchronously with a source of current, having its polarity periodically or frequently reversed, whereby any tendency to deposit metallic mercury upon the shell 17 or the drum 21 will be instantly succeeded and neutralized by an equal energetic tendency to throw any deposited metal off the same. The suspended particles of gold and platinum, by reason of the violent agitation of the pulp by the means hereinabove described, and also because of the well known magnetic effect on such loose metallic particles in such a mag-

netic field, the said magnetic effect being that said metallic particles assume a like polarity to that of its dominating neighbor at the instant of contiguity and consequently repellent thereto, combine with the precipitating metallic mercury, while the exciting surfaces of the shell 17 and the toothed drum 21 remain practically clear of mercury or amalgam, thus obviating the necessity of scraping off said amalgam to recover the values therefrom. The advantage of employing an alternating current or a direct current having its polarity periodically reversed, will also be apparent by the consideration of the fact that the ores of the metals, such as gold, platinum, silver or the like, not infrequently carry copper in a condition capable of solution in the mercuric chlorid and sulfuric acid menstruum, before mentioned. Under the action of electrolysis, which takes place in the shell 17, as above stated, with the use of a direct current passing continuously in one direction, metallic copper will be deposited on the interior of the shell 17, if that were made the negative pole or on the exterior of the drum 21, if it were made the negative pole. To either of these coppered metallic parts, metallic mercury would adhere, requiring the apparatus to be taken apart to remove the copper amalgam. By the use of an alternating current or a direct current having its polarity periodically reversed, the copper and mercury will not be deposited upon the shell or drum, for any tendency to deposit the same thereon when the current has one polarity is repelled when the polarity of the current is reversed. As a result of treating the pulp, as above explained, the fine particles of precious metal, such as gold, and platinum, are combined or coated with the mercury, the pulp carrying the amalgamated particles of precious metals passing through the pipe 35, and into the rotatable tubular shaft 60 to be discharged within the lower portion of the receptacle 61, which is partly filled with metallic mercury. The blades or agitators 62 are rotated at the proper speed, whereby the pulp is continuously agitated so that the mercury coated fine particles of the precious metal may be absorbed by the quantity of metallic mercury at the bottom of the receptacle 61 and the pulp then passes through pipe 68, to be fed into the tubular shaft 60 of the next apparatus also containing metallic mercury. Any required number of the apparatuses containing metallic mercury may be employed, as is found advantageous. In order to prevent the obstruction of the flow of the pulp through the vertical tubular shaft 60, by the lower end thereof being submerged too deeply in the metallic mercury which has a specific gravity considerably exceeding that of the pulp, the tubular shaft 60 may

be vertically adjusted to move the lower end thereof toward and away from the upper surface of the metallic mercury. As the manner in which the vertical shaft 60 operates has already been described it will not be repeated. The precious metals having been thus separated from the ore pulp and retained by the metallic mercury baths in the receptacles 61 as hereinbefore described, 10 the now barren pulp flows out through the pipe 68 to waste.

At desired times the mercury, containing its collected amalgamated values, is drawn out from the receptacles 61 and retorted, or 15 otherwise treated by any of the well known or prepared processes for separating the precious metals from the metallic mercury.

Having described my invention, I claim:—

1. The herein described process, which 20 consists in subjecting finely divided material containing precious metals in fine particles to the action of an aqueous solution of mercuric chlorid, in the presence of a metal which is more readily acted upon by the 25 mercuric chlorid than the fine particles of the precious metal, while subjecting the mass to the action of an electric current having its polarity periodically reversed.

2. The herein described process, which 30 consists in agitating a mixture of finely divided material containing precious metals in fine particles and an aqueous solution of mercuric chlorid and an acid, in the presence of a metal which is more readily acted 35 upon by the aqueous solution of the mer-

curic chlorid and acid than the fine particles of the precious metal.

3. The herein described process which consists in subjecting finely divided material containing precious metals in fine particles 40 to the action of an aqueous solution of mercuric chlorid and sulfuric acid, in the presence of a metal which is more readily acted upon by the mercuric chlorid and sulfuric acid than the fine particles of precious 45 metals.

4. The herein described process, which consists in agitating a finely divided material containing precious metals in fine particles and an aqueous solution of mercuric 50 chlorid and an acid, in the presence of iron, substantially as described.

5. The herein described process, which consists in subjecting finely divided material carrying precious metals in fine particles 55 to the action of an aqueous solution of a mercury salt while subjecting the aqueous solution of the mercury salt to the action of electrolysis whereby the fine particles of precious metal are amalgamated by the metallic mercury, and subsequently passing the material containing the amalgamated particles of precious metal into metallic mercury.

In testimony whereof I affix my signature 65 in presence of two witnesses.

FREDERICK A. WISWELL.
